CHARLES HAUNZ, OF LANCASTER, NEW YORK, ASSIGNOR TO GOULD STORAGE
BATTERY COMPANY, A CORPORATION OF NEW YORK.

STARTING MEANS.

1,385,210.

Specification of Letters Patent. Patented July 19, 1921.

Application filed May 10, 1917. Serial No. 167,678.

To all whom it may concern:

Be it known that I, CHARLES HAUNZ, a subject of the Emperor of Germany, residing in Lancaster, county of Erie, and State of New York, have invented new and useful Improvements in Starting Means, set forth in the annexed specification and drawing, forming a part thereof.

My invention pertains to that class of starting means wherein it is desired that some instrumentality incapable of starting itself shall be put in motion, and is particularly applicable to that class of means employed for winding clocks, operating doors, windows, etc., and starting internal combustion engines, as for example such as now employed for driving automobiles, etc.

My invention pertains more specifically to such means operated by the expansion of heated gases, and comprehends means for generating an explosive mixture, burning and utilizing the power therefrom to perform the desired function.

The drawing shows, partly in section and partly in a diagrammatic manner, one form of starting means embodying the elements of my invention.

In the drawing, 1 represents a T-shaped body casting with an internal cavity 2 with its run horizontal and its branch facing downwardly. One end of the run is closed as by a suitable plug 3 carrying a metallic member 4 insulated therefrom as by bushings 5 clamped between the member 4 and nut 6 in such manner as to form a gas-tight joint with respect to plug 3. The other opening of the run has firmly held therein to form a gas-tight joint, as for example by the screw-thread as shown, a barrel 40 or cylinder 7 provided with a piston 8 attached to one extremity of a piston rod 9 provided with a rack 10 engaging the pinion 11 which is operatively connected with the shaft 12 of the motor, or other device to be started, as by means of any usual type of over-running clutch, the external housing of which is indicated at 13. Details of the over-running clutch are purposely omitted for the sake of clearness, as many such 50 clutches are now well known articles of commerce, it being understood that any type of clutch may be used at 13 which will

drive the shaft 12 when the pinion 11 is rotated in a counter-clockwise direction and allow the pinion to rotate freely in a clockwise direction; or, in other words, allow the shaft 12 to rotate freely with respect to pinion 11 when the said shaft is rotating in a counter-clockwise direction. The entire starting mechanism may be supported 60 in proper relation to the pinion 13, as by means of the lugs or bosses 14, and the thrust of the said gear upon the rack may be provided for by any suitable means, as for example the sheave or roller 15, supported in any desired way by the shaft 16. The piston 8 fits snugly within the bore of the cylinder 7 and is normally pressed in a left-handed direction by any suitable yielding means, in this instance indicated merely 70 as a compression spring 17, within the cylinder, having one end in contact with the piston and the opposite end held in a fixed position as by the screw plug 18. The piston 8 is provided with a tail-rod 19 carrying 75 the insulating member 20, which the spring 17 tends to press against the member 21 carried by the leaf-spring 22, in such manner as to hold the said member 21 against the member 23, which arrests further expansion 80 of the spring 17. The leaf-spring 22 is carried by and in electrical communication with the iron cylinder or electrode 24 which is attached, as by means of the screw-thread shown, to the perforated member or disk 25 85 of a chemically inert insulating material. The said disk 25 is firmly held in the position shown in the drawing as by means of the rod or electrode 26 which is shouldered, as indicated, and screwed into the lug or 90 boss 27 which projects from a side or wall of the internal cavity 2 of the member 1. The iron cup or receptacle 28 closes the branch of the body casting and may be held in place by a screw-thread, as shown, and is preferably filled to about the level indicated in the drawing with an electrolyte, which for example may be considered as a dilute solution of caustic potash. The members 21 and 23 are preferably of platinum or some other 100 conducting material chemically inert and capable of withstanding high temperature and not readily disintegrated by an electric spark,—while spring 22 is preferably of steel

and tends normally to separate the point 21 from the point 23. The member 4 is connected as by wire 29 with one terminal of any suitable battery 30, or other source of current, the opposite terminal of which is connected as by wire 31 with one terminal of a suitable inductance or spark coil 32, the opposite terminal of which is connected as by wire 33 led to one side of a suitable 10 contacting device or switch or key 34, the opposite terminal of which is connected with some portion of the starting device, as indicated by wire 35, or by a usual "ground", or other suitable connection. The piston 8 15 may be provided with a small aperture therethrough, indicated in dotted lines at 36, for a purpose as will hereinafter be explained, and the cylinder 7 is provided with an exhaust port 37 the function of which 20 will hereinafter appear.

An operation of my invention is substantially as follows:

If the shaft 12 be at rest and the other parts of the device in the positions indicated in the drawing, spring 17 will hold the contact 21-23 tightly closed, and the shaft 12 25 may be started by depressing key 34 in the following manner. If we consider the positive terminal of the battery 30 as connected with the wire 29, and the battery of sufficient electromotive force, the making of the contact at 34 will allow current to flow from the battery through 29, member 4, contact 23-21, member 22, electrode 24, and thence 30 through the electrolyte to electrode 26 and cup 28 to wire 35, switch 34, wire 33, coil 32 and wire 31 to the battery. The passage 35 of the current through the electrolyte will rapidly generate a very explosive mixture 40 of oxygen and hydrogen which will accumulate in the cavity 2 until the volume thereof will cause sufficient pressure to be exerted upon the piston 8 that the same will be moved in a right-handed direction against the 45 pressure of the spring 17, whereupon spring 22 will break the contact at 21-23 and cause a spark in the usual manner, which will explode the mixture within the cavity 2 and cause the piston 8 to be driven in a right-handed direction, revolving the pinion 11 and shaft 12 in a counter-clockwise direction, through the instrumentality of the clutch 13, which will allow the motor or other instrumentality connected with the 50 shaft 12 to continue its rotation in this direction, free of the starting mechanism. When the piston 8 passes the exhaust port 37, most of the burnt gases contained in the cavity 2 and portion of the cylinder back 55 of the piston will be allowed to escape, and the spring 17 will tend to restore the piston to the position shown in the drawing, unless arrested by back pressure which will be relieved either by leakage past the piston or slow exhaust through the aperture 36, pro-

vided for this purpose. When this leakage has allowed the spring to return the piston to the position shown in the drawing, another starting impulse may be given by simply again depressing the key or switch 70 34 and completing the circuit therethrough.

From the foregoing it will be noted that I have produced a starting means of very simple construction composed of extremely few movable parts which may be cheaply 75 made and operated at small expense, and particularly applicable to small motors which may be started with a moderate supply of explosive mixture, such as may readily be generated in a short interval of time 80 and with a small expenditure of electrical energy through the instrumentality of my invention.

I do not wish in any way to limit myself to any of the exact constructions or details 85 of operation given above to illustrate an embodiment of my invention, for it will be obvious that wide departure may be made therein without departing from the spirit and scope thereof.

What I claim is:

1. Starting means comprehending electrolytic gas generating means and means operated responsive to pressure of the gas generated for igniting the gas generated to start 95 an element in motion.

2. Starting means comprehending an electrically operated gas generator producing an explosive mixture and means operated by the pressure of the gas generated for igniting 100 said mixture and starting an element in motion.

3. Starting means comprehending an electrically operated gas generator producing an explosive mixture and means for igniting 105 said mixture in said gas generator and utilizing the expansion of the ignited gases.

4. Starting means comprehending an electrically operated gas generator producing an explosive mixture of gases, means for confining 110 said gases under pressure, and means operated responsive to pressure of the gas produced for igniting said confined gases to initiate a movement in a member to be started.

5. Starting means comprehending an electrically operated gas generator producing an explosive mixture of gases, means for confining 115 said gases under pressure, means operated responsive to said production of gas for igniting said confined gases, and means for utilizing the power developed thereby to perform a starting function.

6. Starting means comprehending an electrically operated gas generator producing an 125 explosive mixture of gases, means for confining said gases under pressure, means operated responsive to pressure of the gas produced for igniting said confined gases, and means for utilizing the power developed 130

thereby to perform a starting function comprehending a movable element affected by the expansion of said gases.

7. Starting means comprehending an electrically operated gas generator producing an explosive mixture of gases, means for confining said gases under pressure, means operated by the pressure of the gas produced for igniting said confined gases, and means for utilizing the power developed thereby to perform a starting function comprehending a movable element affected by the expansion of said gases and power transmitting means connected with said element for affecting an element to be started in motion.

8. Starting means comprehending an electrically operated gas generator producing an explosive mixture of gases under pressure, and means for igniting said gases under pressure and causing starting means to become active.

9. Starting means comprehending an electrically operated gas generator producing an explosive mixture of gases under pressure, and means for igniting said gases under pressure affected by motion caused by said pressure and resulting in starting an element from rest.

10. Starting means comprehending an electrically operated gas generator producing an explosive mixture of gases under pressure, means for igniting said gases under pressure affected by motion caused by said pressure, and means for utilizing the power incident to said ignition.

11. Starting means comprehending an electrically operated gas generator producing an explosive mixture of gases under pressure, means for igniting said gases under pressure affected by motion caused by said pressure, and means for utilizing the power due to said ignition comprehending a movable member operated by the expansion due to said ignition, and means for operatively connecting the same with a member to be started in motion.

12. Starting means comprehending an electrically operated gas generator producing an explosive mixture of gases under pressure, means for igniting said gases under pressure affected by motion caused by said pressure, and means for utilizing the power due to said ignition comprehending a movable member operated by the expansion due to said ignition, and means for operatively connecting the same with a member to be started in motion combined with means for permitting the said movable member to return to its operative position after completing its starting function.

13. Starting means comprehending an electrically operated gas generator producing an explosive mixture of gases under pressure, means for igniting said gases under pressure affected by motion caused by said

pressure, and means for utilizing the power due to said ignition comprehending a movable member operated by the expansion due to said ignition, and means for operatively connecting the same with a member to be started in motion combined with means for returning the movable member to its original operative position when its starting function is completed.

14. Starting means comprehending an electrically operated explosive gas generator combined with means operated responsive to the operation of the gas generator for automatically igniting the gases generated thereby and producing motion of a member from rest.

15. Starting means comprehending an electrically operated explosive gas generator combined with means for automatically igniting the gases generated thereby, and means for utilizing the expansion of said gases due to the ignition.

16. Starting means comprehending an electrically operated explosive gas generator combined with means operated responsive to the generation of gas by the gas generator for automatically igniting the gases generated thereby, and means for utilizing the expansion of said gases due to the ignition comprehending a movable member and power transmitting means.

17. Starting means comprehending an electrically operated explosive gas generator combined with means for automatically igniting the gases generated thereby, and means for utilizing the expansion of said gases due to the ignition, comprehending a movable member and power transmitting means combined with means affecting the restoration of the movable member to its original operative position upon completion of its starting function.

18. Starting means comprehending an electrically operated gas generator having an explosion chamber in communication therewith, means communicating with said chamber for igniting the mixture therein, means responsive to the pressure of said mixture for operating said igniting means, and means coöperating therewith to utilize the expansion due to the ignition of gases in said chamber to perform a starting function.

19. Starting means comprehending an electrically operated gas generator having an explosion chamber in communication therewith, means communicating with said chamber for igniting the mixture therein, means responsive to the pressure of said mixture for operating said igniting means, and means coöperating therewith to utilize the expansion due to the ignition of gases in said chamber to perform a starting function comprehending a member to be started and a mechanical connection therewith.

20. Starting means comprehending an electrically operated gas generator having an explosion chamber in communication therewith, means communicating with said chamber for igniting the mixture therein, means responsive to the pressure of said mixture for operating said igniting means,

and means coöperating therewith to utilize the expansion due to the ignition of gases in said chamber to perform a starting function 10 comprehending a member to be started and a mechanical connection therewith for transmitting motion in one direction only.

CHARLES HAUNZ.
